HOOK LEASE REED

Albert J. Owler, Northbridge, Mass., assignor to
American Supply Company, Central Falls,
R. I., a corporation of Rhode Island

Application December 14, 1936, Serial No. 115,667

17 Claims. (Cl. 28—40)

My invention relates to improvements in hook lease reeds. While I am aware that others have provided lease reeds having sets of solder blocks joining alternate dents together near the upper and lower portions thereof to permit the taking of two half leases in the loom beam with a removable top for raising or dropping the yarn into the dent spaces, as shown in Patent No. 495,435 to Simoneau issued April 11, 1893, and others have provided hook lease reeds with open tops but without the solder blocks joining alternate dents together near the lower portions thereof, as shown in British Patent No. 17,023 of 1902 to Eugene Bonnard for taking one and one end leases between the different beams on the creel making up the loom beam, and that it has been standard practice in the trade for many years to provide a hook lease reed embodying both of these leasing features but with the upper portions of the dents rigidly joined together as well as the lower portions thereof, requiring the necessity of twisting in or drawing-in each individual end through the reed, so far as I am aware I am the first to provide a hook lease reed having a removable top to provide a structure having all the advantages of a solid hook lease reed yet permitting the laying-in or dropping-in of the individual ends between the dents and permitting the taking of all types of full or half leases therein regardless of the number of yarn beams employed in making up one loom beam. In the prior art it has been necessary to employ one lease reed to each yarn beam or use the old method of drawing-in or twisting-in through a single hook lease reed, both expensive and laborious methods. In the provision of a hook lease reed of this description it is necessary not only to retain the upper extremities of the dents in longitudinal alignment but it is highly desirable to apply longitudinal compression to the ends of a row of aligned dents to make the upper portions of the dents as rigid as formerly employed in former types of rigid hook lease reeds. To keep the dents in longitudinal alignment, I preferably provide a removable upper cap or rod member having a longitudinal slot therein of substantially the thickness of the dents, and to apply compression to the ends of the row of aligned dents, I preferably provide wedge plates detachably insertable between the usual end plates of the hook lease reed and the ends of the row of longitudinally aligned dents to compress the upper extremities of the longitudinally aligned flexible dents into accurate longitudinal alignment, preferably also employing a type of spacing solder

blocks of equal length soldered to similar end walls thereof to equally space the upper extremities of said dents, said blocks preferably also having upper walls inclined downwardly from said dents to permit the ready laying-in of an end of yarn between each dent. In order to provide a positively rigid structure, I preferably provide means preferably comprising cap members threadedly adjustable on the ends of said rod to compress the upper extremities of said longitudinally aligned plates, wedges and dents to provide a hook lease reed having as rigid an upper portion as the former types of hook lease reeds not provided with removable tops. 5

A further object of my invention is to provide on removal of said wedges and the longitudinally aligning and compressing cap and compressing means a ready longitudinal flexibility of the individual dents to permit the easy laying-in or dropping-in of the requisite number of ends, and during this operation, I preferably provide means or bars for retaining the upper portions of said dents in longitudinal alignment during the removal of said rod or cap for threading in the ends between said dents. Employing my improved type of rigid hook lease reed as against the well-known type of rigid hook lease reed permitting the laying or dropping-in of the ends instead of the twisting-in or drawing-in of the ends, I am enabled to save 50-70% of the time and labor required in setting up a new loom beam from a set of yarn beams based on the total time it is necessary to shut the slasher down in changing over and thereby increasing the total productive capacity of the slasher 30% and permitting the use of less skilled and fewer operators than are required to accurately twist-in or draw-in the ends. 10 20 25 30 35

A further object of my invention is to provide a construction capable of providing a more perfect warp than hitherto possible insuring that all ends be parallel as more accurate control of yarn ends is possible. 40

A further object of my invention is to provide a construction permitting the more ready detection of any end or ends that may be missing on the section beam during the creeling-in operation and a construction which will positively avoid any possibility of crossing ends. 45

Further objects of my invention are to provide a construction permitting more ready access to the warp in case of trouble from piling up which occurs when yarn ends become crossed or due to breakage and one which is easier to fix when the yarn breaks near the reed. In comparison with the new types of double creel systems for 50 55

changing sets of yarn beams to make up a loom beam, it is apparent that employing my improved reed the loom beam may be set up to operate at substantially the same speed as required in said systems without the necessity of the large capital investment or large floor areas required by said systems.

These and such other objects of my invention as may hereinafter appear will be best understood from a description of an embodiment thereof such as shown in the accompanying drawings.

In the drawings, Fig. 1 is a front elevation of a hook lease reed with a removable top constructed in accordance with my invention with the angle bars removed and showing the reed with parts assembled for actual leasing.

Fig. 2 is a vertical sectional view taken along the line 2—2 of Fig. 1.

Fig. 3 is a disassembled front elevation of my improved hook lease reed with the compression means, wedges and removable top removed but with the aligning bars inserted in position for the laying or dropping in of the ends in the spaces between the individual dents, parts of the cap members and rods being shown in section.

Fig. 4 is a detailed sectional view taken along the line 4—4 of Fig. 3.

In the drawings, wherein like characters of reference indicate like parts throughout, 10 generally indicates a hook lease reed having a removable top constructed in accordance with my invention. Said reed includes a row 12 of longitudinally aligned dents 14 and flat end plates 16 of substantially the thickness of said dents and means to join the lower extremities of said row 12 of longitudinally aligned dents and end plates in longitudinal alignment, in my preferred embodiment comprising a longitudinally split tube 19, into the longitudinal split 17 of which the lower extremities of the longitudinally aligned dents are secured preferably by solder at equally spaced longitudinal distances by means preferably comprising a lower helical spring 18 and an upper helical spring 20, each having the winds thereof interposed between adjacent dents and suitably soldered thereto by the solder 22, the lower extremities of said flat end plates being also soldered within said split tube 19 by the solder 24 exterior of the ends of said row of aligned dents. In my preferred embodiment, to provide a more desirable construction I provide the intermediate flat socket plates 26 also substantially the thickness of said dents and also having the lower extremities thereof soldered within said split tube 19 at spaced longitudinal distances from opposite ends of said row of aligned dents. In the preferred embodiment said socket plates 26 are provided with aligned bar receiving studs 30 projecting from each side thereof near the upper end thereof and receiving sockets 32 near the upper inner ends thereof, in the preferred embodiment said sockets 32 being provided by having the upper ends of said plates 26 cut away as at 34, at each inner end thereof, with the upper end of each socket plate below said cut-away portion having a vertical notch 36 therein and guideway forming plates 38 secured to each side wall of each plate on opposite sides of said notch 36, forming the vertical socket 32 with said vertical notch 36. In the event that the socket plates 26 be omitted, the end plates 16 are similarly spaced from each end of the row of aligned dents for the insertion of the wedge means 40, to be described between the inner ends thereof and the outer ends of the aligned row of dents, instead of between the

inner ends of said socket plates 26 and the outer ends of said row 12 of dents 14. If the socket plates 26 be employed, the lower extremities of the flat socket plates 26 and the lower extremities of the flat end plates 16 are suitably soldered within said split tube by the solder 24.

It is thus obvious that with this construction a certain amount of longitudinal flexibility of the upper extremities of the aligned row of dents is permitted and to equally space the upper extremities of said dents and to provide means to permit the relative longitudinal tilting of said dent upper extremities, said dents have the blocks 42 of equal length soldered to similar end walls 44 thereof, said blocks 42 having upper walls 46 inclined downwardly from said dents.

Said dents 14 are also provided with a hook 48 projecting downwardly at a spaced distance from each dent. While said hooks may be constructed in any convenient manner, in my preferred embodiment the blocks 42 are preferably provided with recesses 50 in the lower walls thereof adjacent said dents and the hooks 48 comprise the strips 52 having the upper extremities 54 thereof soldered within said recesses 50 and the lower hook forming tips 48 thereof projecting downwardly at spaced distances from each dent and to accurately space said tips 48 substantially midway of adjacent dents, the solder blocks 56 are provided vertically spaced from the lower tips 48 of said hooks to join the lower portions of said strips 52 to said similar dent surfaces. It is obvious that with this construction a hook lease reed is provided capable of taking a full one to one lease. If it be also desired to provide a hook lease reed capable of taking half leases, solder blocks 60 are preferably provided joining opposite alternate dents together near the lower portions thereof and if desired similar staggered alternate supplemental hooks and solder blocks may be provided to join opposite alternate dents together near the upper portions thereof to facilitate manufacture of some special warps.

As stated hitherto, in order to rigidly compress the upper extremities of said dents together in longitudinal alignment, I provide the longitudinal wedge plates 40, also of substantially the thickness of said dents adapted to be interposed between said row of longitudinally aligned dents and socket plates 26, if employed, or end plates 16 if said socket plates 26 be not employed, having outer end walls 64 adapted to abut the inner end walls of said socket plates 26 or end plates 16 and terminating in inner end walls having lower upwardly inclined cam portions 66 and substantially vertical upper locking portions 68 adapted to abut the outer ends of said aligned row of dents and compress them into substantially vertical alignment. As stated hitherto, the sockets 32 are preferably provided near the inner walls 60 of said socket plates for receiving projections 65 from the outer ends of said wedge plates 40, each projection 65 being formed by providing a vertical notch 70 in the lower wall thereof spaced from the outer end wall thereof to provide the downward projection 65 to compactly fit within each socket 32.

As stated hitherto, I also provide a removable cap member 62 provided with a longitudinal slot 72 therein of substantially the thickness of said dents 14, wedges 40 and plates 16 and/or 26 for receiving the upper extremities of said dents, wedges and plates and supplementally retaining them in longitudinal alignment. For a purpose to be described, said rod 62 is preferably provided

with the externally threaded ends 14. As also stated hitherto, I provide means to longitudinally compress the upper extremities of said aligned dents, wedges and plates to provide a hook lease reed having a rigid upper portion and in my preferred embodiment said means comprises the hollow cap members 76 internally threaded as at 78 for receiving each externally threaded end of said rod cap member 62 having inwardly projecting circular inner annular lips 80 adapted to rotate within and abut the inner surfaces of notches 82 cut in the outer end walls of the end plates 16 near the upper extremities thereof to longitudinally compress the upper extremities 15 of said aligned plates, wedges and dents between said opposite cap members 76 to provide a hook lease reed having a rigid upper portion. The annular projections 80 and notches 82 are provided to prevent the cap members 76 from riding 20 upwards on the end plates as compression is exerted thereon.

In order to lay in or drop in the ends of yarn in the spaces between the dents 14, the slotted cap member or rod 62 is removed after releasing 25 compression from or total removal of the cap nut members 76 therefrom and the wedges 40 are removed from their sockets to permit longitudinal flexibility of the upper ends of said dents so that they may conveniently receive the ends 30 of yarn between them, and in order to retain the row of dents in substantially longitudinal alignment, I provide suitable bars 86 in the preferred embodiment the L-bars shown having notches 84 therein for receiving the aligning studs 30 35 therein so that said bars may abut the side walls of the aligned dents for retaining the upper portions of said dents in longitudinal alignment while laying-in the ends of yarn between said dents.

40 It is thus obvious that after the ends of yarn are laid between said dents, the wedges 40 are re-inserted to compress the dents into substantially vertical alignment, the outer ends 64 of said wedges bearing against the inner ends of 45 said flat plates for this purpose and the upper extremities of said dents being equally spaced by the flat free end walls 45 of said blocks 42 abutting adjacent dent end wall portions after which the cap member 62 may be inserted over 50 the upper extremities of said aligned dents, wedges and plates, the upper extremities of said aligned dents, wedges, and plates compactly fitting within the longitudinal slot 72 therein and the end cap members 76 screwed on to the extremities of said rod 62 to longitudinally compress the upper extremities of said thus aligned upper extremities of said dents, wedges and plates to provide a hook lease reed having a positively rigid upper portion. Then the bars 86 55 being no longer necessary, may be removed and the desired half leases or full leases taken as is customary in the trade for hook lease reeds, otherwise known as Scotch hook reeds in the following manner.

60 In the making up of a warp for the ultimate weaving of cloth it is necessary to combine a multitude of separate ends of yarn onto one large beam or spool. This spool is then placed in the loom, woven together with the filling to produce 65 a strong interwoven web or fabric.

The large spool or beam of warp yarn is made up by combining the yarn from several other large spools, each containing a given number of ends of yarn. The number of ends of yarn to 70 be combined together in forming one warp are

dependent on the type of cloth to be woven. In so combining a large number of ends of yarn together, difficulty is experienced in keeping each piece of yarn in proper relation to its neighbors especially in the cotton process of warping where 5 the separate sheets of yarn from several smaller spools or beams are passed through a slasher which impregnates the yarn with a sizing beneficial to the yarn in the weaving process. Size is an organic material in liquid form and a substance which has some adhesive qualities. If the mass of yarn ends were allowed to pass through the slasher without being separated one from the other, several ends could become crossed thereby causing trouble in the weaving operation. To 15 keep the yarn straight and parallel in this operation a device called a hook reed is used. In the use of this reed the yarn from each separate beam to be combined together to make the whole warp, is introduced into the reed by placing one 20 end of yarn into each dent space. The beam is made up to conform to the number of dents in the reed. Any number of beams may be used but it is necessary that an even number of ends be introduced into each dent space. 25

The hook reed itself is composed of a number of parallel vertical dents. Every other dent at the bottom side of the reed is joined together with a block of solder. Each dent on the top side of the reed has a thin flat dent wire attached to it but separated in such a manner as to form a short hook. The yarn may be passed into the space between the hook and the dent, bottoming against the block which fastens the hook onto the dent wire. Again by pressing the 35 yarn to the opposite side of the dent space, the yarn is free to pass into the space between the hook and the next dent and pass freely to the top of the reed. Means therefore are presented which enables an operator to split the combined 40 spools which form the warp into separate sheets of yarn and by splitting these, as will be described, to keep the yarn in its proper relation one end to the other. In operation the reed is drawn-in, twisted-in or layed-in. These terms 45 simply mean that the separate yarn ends are separately introduced into the proper dent space in the reed. As each complete beam is introduced to the reed in its entirety a rod is so arranged between the beam and the reed as to have 50 the yarn pass over it forming a separate sheet of yarn. Each beam is so treated. After all beams are thus introduced to the reed the combined ends of yarn are split half and half. This is done by pressing the ends of yarn to the 55 bottom of the reed. Half the ends go no further than the blocks at the bottom of the reed and the other half pass down to the rib or bottom of the reed. On the side of the reed towards the slasher a small tunnel or space is thus formed 60 through which a rod may be passed and followed through by a string. This process is called taking a half lease. The ends of yarn are again moved into the center of the reed and the yarn moved into the machine a short way to provide equal 65 tension on all ends. The operator then stops the movement of the yarn and proceeds to take a full lease in the warp. He does this as follows. The sheet formed by the beam furthest away from the reed is separated from its fellows by the rod 70 previously inserted. The rod is grasped by the operators and brought toward the reed being thrust slightly to the hook side of the dents. This pushes the yarn against the side of the dents in the reed. When all ends are in contact with the 75

reed a slight upward movement is made and the 5
yarn end brought up against the block which fastens the hook wire. The rod is then placed in a bracket in such a manner as to produce a strain 10
on the yarn sufficient to hold it in place. The
next sheet of yarn is treated in a like manner, 15
but the thrust movement is to the opposite side.
The upward movement this time allows the yarn
to pass the hook and rest against the top of the
reed. Alternate succeeding beams are treated
likewise. At the conclusion of this operation half
the ends of yarn are resting in the hook space
and the other half are at the top of the reed.
Each individual yarn end is in correct relation to
the other yarn ends. Again a tunnel of triangular
space is formed at the machine side of the
reed. The rod and string are introduced. The
rod is removed leaving the string in place. This
gives a (one and one) half lease. The lease is
completed by reversing the process, i. e., the first
beam or beam furthest away from the reed is
passed by the hooks to the top of the reed, the
second is passed into the hooks, etc. Through
the tunnel or space formed by thus splitting the
warp a rod and string are passed. The rod is
again removed leaving the string in place. Thus
we have taken two half leases (one and one).
Two adjacent ends of yarn in cross section would
appear as shown below. The formation of the
web or double X is kept intact by the two in-
30
serted strings and the whole warp may now be
passed all the way through the slasher without
the relation of one end of yarn to another being
disturbed. In other words, the 55th end on each
beam and all ends will be parallel throughout
35
passage through the machine.

To remove the ends from the lease-reed it is
obvious that it is merely necessary to unscrew
the cap members 76, remove the rod 62 and
40
wedges 40, and by bearing the ends of yarn
against the free dent end surfaces, they may be
raised upwards past the hook tips 48 by the flex-
ing of the individual dents past the blocks 42.

It is understood that my invention is not limited
45
to the specific embodiment shown and that
various deviations may be made therefrom with-
out departing from the spirit and scope of the
 appended claims.

What I claim is:

50 1. A hook lease reed comprising, a row of
longitudinally aligned dents, flat end plates of
substantially the thickness of said dents and
means to joint the lower extremities of said row
55 of longitudinally aligned dents and end plates
in longitudinal alignment, the upper extremities
of said dents having blocks of equal length sold-
ered to similar end walls thereof, said blocks
having upper walls inclined downwardly from
60 said dents and hooks projecting downwardly
from said similar end surfaces of said dents, hav-
ing lower hook forming tips projecting down-
wardly at spaced longitudinal distances from
each of said dents, a rod having a longitudinal
slot therein of substantially the thickness of said
65 dents and plates for receiving the upper extremi-
ties of said dents and plates and retaining them
in longitudinal alignment and having externally
threaded ends and internally threaded cap mem-
bers for each end of said rod having inner ends
70 adapted to abut the outer ends of said end plates.

75 2. A hook lease reed comprising, a row of
longitudinally aligned dents, flat end plates of
substantially the thickness of said dents aligned
therewith, and means to join the lower extremi-
ties of said row of longitudinally aligned dents
75 ties of said row of longitudinally aligned dents

and end plates in longitudinal alignment, the
upper extremities of said dents having blocks of
equal length soldered to similar end walls there-
of, said blocks having upper walls inclined down-
wardly from said dents and hooks projecting 5
downwardly from said similar end surfaces of
said dents having lower hook forming tips pro-
jecting downwardly at spaced longitudinal dis-
tances from each of said dents, longitudinal
wedge plates also of substantially the thickness 10
of said dents adapted to be longitudinally inter-
posed between said row of longitudinally aligned
dents and end plates having outer end walls
adapted to abut the inner end walls of said end
plates and inner end walls adapted to abut the 15
outer ends of said aligned row of dents and com-
press them into substantially vertical alignment,
and a rod having a longitudinal slot therein of
substantially the thickness of said dents, wedges
and plates for receiving the upper extremities of 20
said dents, wedges and plates and retaining them
in longitudinal alignment.

3. A hook lease reed comprising, a row of lon-
gitudinally aligned dents, flat end plates of sub-
stantially the thickness of said dents and means 25
to join the lower extremities of said row of lon-
gitudinally aligned dents and end plates in lon-
gitudinal alignment, the upper extremities of said
dents having blocks of equal length soldered to
similar end walls thereof, said blocks having upper 30
walls inclined downwardly from said dents and
hooks projecting downwardly from said similar
end surfaces of said dents, having lower hook
forming tips projecting downwardly at spaced
longitudinal distances from each of said dents, 35
and means to longitudinally compress the upper
extremities of said aligned plates and dents to-
gether to provide a hook lease reed having a
rigid upper portion.

4. A hook lease reed comprising, a row of lon-
gitudinally aligned dents, flat end plates of sub-
stantially the thickness of said dents aligned 40
therewith and means to join the lower extremities
of said row of longitudinally aligned dents and
end plates in longitudinal alignment, the upper
45
extremities of said dents having blocks of equal
length soldered to similar end walls thereof, said
blocks having upper walls inclined downwardly
from said dents and hooks projecting downwardly
from said similar end surfaces of said dents, 50
having lower hook forming tips projecting down-
wardly at spaced distances from each dent and
longitudinal wedge plates also of substantially
the thickness of said dents adapted to be lon-
gitudinally interposed between said row of lon-
55
gitudinally aligned dents and end plates having
outer end walls adapted to abut the inner end
walls of said end plates and terminating in inner
end walls having lower upwardly inclined cam
portions and substantially vertical upper locking
60 portions adapted to abut the outer ends of said
aligned row of dents and compress them into sub-
stantially vertical alignment.

5. A hook lease reed comprising, a row of lon-
gitudinally aligned dents, flat end plates of sub-
stantially the thickness of said dents aligned 65
therewith and means to join the lower extremities
of said row of longitudinally aligned dents and
end plates in longitudinal alignment, the upper
extremities of said dents having blocks of equal
length soldered to similar end walls thereof, said
blocks having upper walls inclined downwardly
from said dents and hooks projecting downwardly
from said similar end surfaces of said dents,
having lower hook forming tips projecting down-
75

- wardly at spaced distances from each dent and longitudinal wedge plates also of substantially the thickness of said dents adapted to be longitudinally interposed between said row of longitudinally aligned dents and end plates having outer end walls adapted to abut the inner end walls of said end plates and terminating in the inner end walls adapted to abut the outer ends of said aligned row of dents and compress them into substantially vertical alignment.

6. A hook lease reed comprising, a row of longitudinally aligned dents, flat socket plates of substantially the thickness of said dents, means to secure the lower extremities of said dents and plates in longitudinal alignment with said socket plates at spaced longitudinal distances from opposite ends of said row of aligned dents, said socket plates having the upper ends thereof cut away at each inner end thereof with the upper end of each socket plate below said cut away portion having a vertical notch therein and guideway forming plates secured to the side wall of each plate on opposite sides of said notch forming a vertical socket with said vertical notch, flat end plates of substantially the thickness of said dents and means to join the lower extremities of said end plates in longitudinal alignment with said row of longitudinally aligned dents, the upper extremities of said dents having blocks of equal length soldered to similar end walls thereof, said blocks having upper walls inclined downwardly from said dents and hooks projecting downwardly from said similar end surfaces of said dents, having lower hook forming tips projecting downwardly at spaced longitudinal distances from each of said dents, longitudinal wedge plates also of substantially the thickness of said dents having vertical notches in the lower wall thereof spaced from the outer end walls thereof to provide downward projections to compactly fit within each socket, and having inner walls adapted to abut the outer ends of said aligned row of dents and compress them into substantially vertical alignment, a rod having a longitudinal slot there-in of substantially the thickness of said dents, wedges and plates for receiving the upper extremities of said dents, wedges and plates and retaining them in longitudinal alignment and having externally threaded ends, and internally threaded cap members for each end of said rod having inwardly projecting annular inner ends adapted to abut the outer ends of said end plates to longitudinally compress the upper extremities of said aligned plates, wedges and dents to provide a hook lease reed having a rigid upper portion.

7. A hook lease reed comprising, a longitudinally split tube, a row of longitudinally aligned dents having the lower extremities thereof soldered at equally spaced longitudinal distances within said split tube, flat end plates of substantially the thickness of said dents having the lower extremities thereof soldered within said split tube exterior of said dents, the upper extremities of said dents having blocks of equal length soldered to similar end walls thereof, said blocks having upper walls inclined downwardly from said dents and hooks projecting downwardly from said similar end surfaces of said dents, having lower hook forming tips projecting downwardly at spaced longitudinal distances from each of said dents, longitudinal wedge plates also of substantially the thickness of said dents adapted to be longitudinally interposed between said row of longitudinally aligned dents and end plates having outer end walls adapted to abut the inner end walls of said end plates and inner end walls adapted to abut the outer ends of said aligned row of dents and compress them into substantially vertical alignment and means to longitudinally compress the upper extremities of said aligned plates, wedges, and dents, to provide a hook lease reed having a rigid upper portion.

8. A hook lease reed comprising, a row of longitudinally aligned dents, flat end plates of substantially the thickness of said dents aligned therewith and means to join the lower extremities of said row of longitudinally aligned dents and end plates in longitudinal alignment, the upper extremities of said dents having blocks of equal length soldered to similar end walls thereof, said blocks having upper walls inclined downwardly from said dents and hooks projecting downwardly from said similar end surfaces of said dents, having lower hook forming tips projecting downwardly at spaced longitudinal distances from each of said dents, longitudinal wedge plates also of substantially the thickness of said dents adapted to be longitudinally interposed between said row of longitudinally aligned dents and end plates having outer end walls adapted to abut the inner end walls of said end plates and adapted to abut the outer ends of said aligned row of dents and compress them into substantially vertical alignment, a rod having a longitudinal slot therein of substantially the thickness of said dents, wedges and plates for receiving the upper extremities of said dents, wedges and plates and retaining them in longitudinal alignment and having externally threaded ends and internally threaded cap members for each end of said rod having inwardly projecting annular inner ends adapted to abut the outer ends of said end plates to longitudinally compress the upper extremities of said aligned plates, wedges and dents to provide a hook lease reed having a rigid upper portion.

9. A hook lease reed comprising, a row of longitudinally aligned dents, flat socket plates of substantially the thickness of said dents, means to secure the lower extremities of said dents and plates in longitudinal alignment with said socket plates at spaced longitudinal distances from opposite ends of said row of aligned dents, said socket plates having the upper ends thereof cut away at each inner end thereof with the inner end of each socket plate below said cut away portion having a vertical notch therein and guideway forming plates secured to the side wall of each plate on opposite sides of said notch forming a vertical socket with said vertical notch, the upper extremities of said dents having blocks of equal length soldered to similar end walls thereof, said blocks having upper walls inclined downwardly from said dents and hooks projecting downwardly from said similar end surfaces of said dents, having lower hook forming tips projecting downwardly at spaced longitudinal distances from each of said dents, longitudinal wedge plates also of substantially the thickness of said dents having vertical notches in the lower walls thereof spaced from the outer end walls thereof to provide downward projections to compactly fit within each of said sockets, adapted to abut the outer ends of said aligned row of dents and compress them into substantially vertical alignment, and means to longitudinally compress the upper extremities of said aligned plates, wedges and dents to provide a hook lease reed having a rigid upper portion.

10. A hook lease reed comprising, a row of longitudinally aligned dents, flat end plates of substantially the thickness of said dents aligned therewith and means to join the lower extremities of said row of longitudinally aligned dents and end plates in longitudinal alignment, the upper extremities of said dents having blocks of equal length soldered to similar end walls thereof, said blocks having upper walls inclined 5 downwardly from said dents and hooks projecting downwardly from said similar end surfaces of said dents, having lower hook forming tips projecting downwardly at spaced longitudinal distances from each of said dents, longitudinal 10 wedge plates also of substantially the thickness of said dents adapted to be longitudinally interposed between said row of longitudinally aligned dents and end plates having outer end walls adapted to abut the inner end walls of said end 15 plates and inner end walls adapted to abut the outer ends of said aligned row of dents and compress them into substantially vertical alignment, means to longitudinally compress the upper extremities of said aligned plates, wedges and dents 20 to provide a hook lease reed having a rigid upper portion and means for retaining the upper portions of said dents in longitudinal alignment during removal of said compressing means and wedges for laying-in the ends between said dents. 25
11. A hook lease reed comprising, a row of longitudinally aligned dents, flat end plates of substantially the thickness of said dents aligned therewith and means to join the lower extremities of said row of longitudinally aligned dents and end plates in longitudinal alignment, the upper extremities of said dents having blocks of equal length soldered to similar end walls thereof, said blocks having upper walls inclined downwardly from said dents and hooks projecting 30 downwardly from said similar end surfaces of said dents, having lower hook forming tips projecting downwardly at spaced longitudinal distances from each of said dents, longitudinal wedge plates also of substantially the thickness of said dents adapted to be longitudinally interposed between said row of longitudinally aligned dents and end plates having outer end walls adapted to abut the inner 35 end walls of said end plates and inner end walls adapted to abut the outer ends of said aligned row of dents and compress them into substantially vertical alignment, and means to longitudinally compress the upper extremities of said aligned plates, wedges and dents to provide a 40 hook lease reed having a rigid upper portion. 45
12. A hook lease reed comprising, a longitudinally split tube, a row of longitudinally aligned dents having the lower extremities thereof soldered at equally spaced longitudinal distances 50 within said split tube, flat socket plates of substantially the thickness of said dents having the lower extremities thereof soldered within said split tube at spaced longitudinal distances from opposite ends of said row of aligned dents having 55 aligned studs projecting laterally from each side thereof near the upper ends thereof and the upper ends thereof cut away at each inner end thereof with the outer end of each guide plate below said cut away portion having a vertical 60 notch therein and guideway forming plates secured to the side wall of each plate on opposite sides of said notch forming vertical sockets with said vertical notch, flat end plates of substantially the thickness of said dents having the 65 lower extremities thereof also soldered within said split tube exterior of said flat socket plates, and notches in the upper portions of the outer ends thereof, the upper extremities of said dents having blocks of equal length soldered to similar 70 end walls thereof, said blocks having upper walls inclined downwardly from the upper ends of said dents and recesses in the lower walls thereof adjacent said dents, hooks projecting downwardly from said similar end surfaces of said dents, comprising strips having the upper extremities thereof soldered within said recesses and lower hook forming tips projecting downwardly at spaced distances from each of said dents and solder blocks 75 spaced from the lower tips of said hooks joining 76

the lower portions of said strips to said similar dent end surfaces and solder blocks joining alternate dents together near the lower portions thereof, longitudinal wedge plates also of substantially 5 the thickness of said dents having vertical notches in the lower walls thereof spaced from the outer end walls thereof to provide downward projections to compactly fit within each socket, and inner end walls having lower upwardly inclined 10 cam portions and substantially vertical upper locking portions adapted to abut the outer ends of said aligned row of dents and compress them into substantially vertical alignment, a rod having a longitudinal slot therein of substantially 15 the thickness of said dents, wedges and plates for receiving the upper extremities of said dents, wedges and plates and retaining them in longitudinal alignment and having externally threaded ends, internally threaded cap members for 20 each end of said rod having inwardly projecting annular inner ends adapted to abut the notches in the outer ends of said end plates to longitudinally compress the upper extremities of said aligned plates, wedges and dents to provide a 25 hook lease reed having a rigid upper portion and bars having notches therein for hooking on said aligned studs for retaining the upper portions of said dents in longitudinal alignment during removal of said rod for laying-in the ends between 30 said dents.

15. A hook lease reed comprising, a row of longitudinally aligned dents, flat end plates of substantially the thickness of said dents and means to join the lower extremities of said row of longitudinally aligned dents and end plates in longitudinal alignment, the upper extremities of said dents having spacing means of equal length projecting from end walls thereof, said means having upper walls inclined downwardly from said 35 dents and hooks projecting downwardly from said end walls of said dents having lower hook forming tips projecting downwardly at spaced longitudinal distances from each of said dents, a rod having a longitudinal slot therein of substantially the thickness of said dents and plates for receiving the upper extremities of said dents and plates and retaining them in longitudinal alignment and having externally threaded ends 40

and internally threaded cap members for each end of said rod having inner ends adapted to abut the outer ends of said end plates.

16. A hook lease reed comprising, a row of longitudinally aligned dents, flat end plates of substantially the thickness of said dents aligned therewith, and means to join the lower extremities of said row of longitudinally aligned dents and end plates in longitudinal alignment, the upper extremities of said dents having spacing 10 means of equal length projecting from end walls thereof, said means having upper walls inclined downwardly from said dents and hooks projecting downwardly from said end walls of said dents having lower hook forming tips projecting 15 downwardly at spaced longitudinal distances from each of said dents, longitudinal wedge plates also of substantially the thickness of said dents adapted to be longitudinally interposed between said row of longitudinally aligned dents 20 and end plates having outer end walls adapted to abut the inner end walls of said end plates and inner end walls adapted to abut the outer ends of said aligned row of dents and compress them into substantially vertical alignment, and a rod 25 having a longitudinal slot therein of substantially the thickness of said dents, wedges and plates for receiving the upper extremities of said dents, wedges and plates and retaining them in longitudinal alignment. 30

17. A hook lease reed comprising, a row of longitudinally aligned dents, flat end plates of substantially the thickness of said dents and means to join the lower extremities of said row of longitudinally aligned dents and end plates 35 in longitudinal alignment, the upper extremities of said dents having spacing means of equal length projecting from end walls thereof, said means having upper walls inclined downwardly from said dents and hooks projecting downwardly from said end walls of said dents, having lower hook forming tips projecting downwardly at spaced longitudinal distances from each of said dents, and means to longitudinally compress the upper extremities of said aligned plates and 40 dents together to provide a hook lease reed having a rigid upper portion. 45

ALBERT J. OWLER.
